UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ART OF ROLLING AND SHEARING METAL BILLETS OR BARS.

Application filed November 22, 1819. Serial No. 339,849.

To all whom it may concern:

Be it known that I, VICTOR E. EDWARDS, a citizen of the United States, residing at Worcester, in the county of Worcester and Commonwealth of Massachusetts, have invented a new and useful Improvement in the Art of Rolling and Shearing Metal Billets or Bars, of which the following, together with the accompanying drawings, is 10 a specification.

The present invention relates to the rolling and shearing of metal billets or bars.

In ordinary practice, the continuous production of metal billets or bars by rolling involves the progressive and uninterrupted diminution of the cross section of the stock, until it emerges from the final pass of the continuous billet, merchant or similar mill in the cross sectional form desired for the 20 finished billets or bars. The stock thus completely reduced, while it is yet emerging from the rolls, is acted upon by a suitable cutting device, known as a flying shear, which divides the same into finished commercial billets or bars of predetermined 25 equal lengths and weights.

The output of a billet, merchant or similar mill of the type above described is limited by the speed at which the flying shear can 30 operate. Ordinarily, such a mill can handle the output of a blooming mill which produces up to say one hundred tons per hour. The modern tendency, however, is to operate blooming mills at an increased 35 tonnage capacity; this is done by giving the blooming mill ample power to insure speed, and by transferring more of its work of reduction to the billet, merchant or similar mill.

40 If it be attempted to speed up the ordinary above described continuous billet, merchant or similar mill sufficiently to take care of this increased tonnage, a difficulty is at once encountered in the production of billets or bars of relatively small section, say of less than four square inches area. This difficulty arises out of the fact that the delivery of completely reduced stock from the final rolls of such a mill, in producing these 45 small sections, would be so rapid as to exceed the limit of speed at which the flying shear can operate. In other words, at the highest speed at which a flying shear can

operate, it is impossible for the ordinary billet, merchant or similar mill, rolling down to sections of less than four square inches, to keep out of the way of the output of a modern high tonnage blooming mill. 55

In order to meet the large demand for billets or bars of smaller sections, and at 60 the same time provide a mill that will take care of the output of a modern high tonnage blooming mill, it is proposed by the present invention to introduce a variation in the usual billet or merchant mill procedure of 65 first reducing the stock completely and thereafter cutting it into the desired lengths. This variation involves a rearrangement of the usual mill apparatus employed in the elongation, reduction and cutting of the 70 stock, and for the purpose of illustrating one way in which the invention is susceptible of being put into practice, the single figure of the accompanying drawings may be referred to as a diagrammatic showing of the 75 new arrangement.

In the billet or merchant mill, as illustrated in said figure, a train of rolls 1, 1 is shown as providing the requisite number of 80 passes for the reduction of the stock to a section somewhat larger than that contemplated for the smaller finished billets or bars. As the stock emerges from the rolls 1, 1, it is acted upon by a flying shear 2, the operation of which may be controlled by 85 any well known form of trigger or measuring device, and is set so as to procure the division of the stock by the shear into pieces that correspond in weight to the bars or billets desired to be produced, but which 90 pieces are shorter and of greater cross section than said finished bars or billets; apparatus of this type is shown and described, for instance, in United States Letters Patent to Edwards, No. 1,104,349, dated July 95 21, 1914, and since said apparatus, of itself, forms no part of the present invention, a detailed description thereof is unnecessary. The shearing of the stock is thus accomplished at an intermediate point in the reduction of the same where the speed of the 100 stock is within the speed limit of the shear, thus enabling the latter to operate, notwithstanding the fact that the rolls 1, 1 are handling, and keeping up with, the entire 105 output of the blooming mill. Following the

shearing operation at this intermediate point in the reduction of the billets, the stock is delivered by suitable conveying devices 3 to one or more additional stands of reducing rolls 4, 4, arranged continuously or in tandem, wherein the final reduction of the short sheared pieces to billets or bars of the desired small cross section is effected, following which said finished bars or billets are delivered to the usual cooling bed, not shown.

It will be obvious that with any given speed limit on the operation of the flying shear 2, the capacity of a billet mill for the production of small cross sections is increased, by my invention, substantially in the proportion that the area of a stock at the point of shearing bears to the area of the stock at the point of finishing. For example, in the production of one and one-half inch billets, or bars, if the shearing be done at a section two inches square, the tonnage output of such billets, or bars, would be increased upwards of seventy-five per cent with any given speed limit of the shear; in other words, the tonnage capacity of the billet, merchant or similar mill as above described would be seventy-five per cent greater than the tonnage capacity of a billet, merchant or similar mill of the ordinary type.

10 I claim,

1. The improvement in the art of continuously rolling and shearing hot metal bars or billets, which consists in rolling the bars in a continuous mill, and simultaneously cutting up the bars by a flying shear before the continuous rolling is completed, whereby to permit finishing of the bars to the desired size while travelling at a speed beyond the operating limit of said shear.

2. In the production of billets or bars of small cross section, by hot rolling in a continuous mill, the improvement which consists in cutting the stock transversely, before the reduction thereof is completed, into short pieces that correspond in weight to the finished billets or bars.

3. In a continuous billet mill for the reduction of blooms to bars or billets of relatively small cross-section, cut to predetermined lengths, the combination with reducing rolls operable successively on the stock, of a flying shear operable on the stock in process of reduction and before it reaches the final reducing rolls of the continuous mill, whereby to permit passage of the stock through said final reducing rolls at a speed beyond the operating limit of said shear.

4. The improved method of producing billets or bars of relatively small cross-section, by hot rolling in a continuous billet mill, which consists in cutting the stock in said billet mill by a flying shear at an intermediate point in its reduction, and thereafter completing the reduction of the short severed pieces at a speed beyond the operating limit of said shear, whereby to make the capacity of said mill independent of the operating speed limit of said shear.

5. In the art of continuously rolling bars or billets of small cross section, improvement which consists in procuring transverse severance of the stock into short pieces at corresponding weight to the finished commercial bars or billets, while in process of reduction by said continuous rolling.

6. The herein described new method of rolling and shearing metal bars and billets, which consists in roughing the stock in a continuous mill, shearing it to finished weights in a flying shear and then finishing the sheared pieces in one or more additional roll passes.

7. In the production of rolled bars and billets of predetermined equal lengths, the improvement which consists in shearing the stock to the finished weights one or more roll passes in advance of the finishing, thereby permitting full freedom of reduction in the finishing roll passes.

Signed this 15th day of November, 1919.

VICTOR E. EDWARDS.

shearing operation at this intermediate point in the reduction of the billets, the stock is delivered by suitable conveying devices 3 to one or more additional stands of reducing 5 rolls 4, 4, arranged continuously or in tandem, wherein the final reduction of the short sheared pieces to billets or bars of the desired small cross section is effected, following which said finished bars or billets are 10 delivered to the usual cooling bed, not shown.

It will be obvious that with any given speed limit on the operation of the flying shear 2, the capacity of a billet mill for the production of small cross sections is increased, by my invention, substantially in the proportion that the area of a stock at the point of shearing bears to the area of the stock at the point of finishing. For example, in the production of one and one-half inch billets, or bars, if the shearing be done at a section two inches square, the tonnage output of such billets, or bars, would be increased upwards of seventy-five per cent with any given speed limit of the shear; in other words, the tonnage capacity of the billet, merchant or similar mill as above described would be seventy-five per cent greater than the tonnage capacity of a billet, merchant or similar mill of the ordinary type.

20 I claim,

1. The improvement in the art of continuously rolling and shearing hot metal bars or billets, which consists in rolling the bars in a continuous mill, and simultaneously cutting up the bars by a flying shear before the continuous rolling is completed, whereby to permit finishing of the bars to the desired size while travelling at a speed beyond the operating limit of said shear.

2. In the production of billets or bars of small cross section, by hot rolling in a continuous mill, the improvement which consists in cutting the stock transversely, before the reduction thereof is completed, into short pieces that correspond in weight to the finished billets or bars.

3. In a continuous billet mill for the reduction of blooms to bars or billets of relatively small cross-section, cut to predetermined lengths, the combination with reducing rolls operable successively on the stock, of a flying shear operable on the stock in process of reduction and before it reaches the final reducing rolls of the continuous mill, whereby to permit passage of the stock through said final reducing rolls at a speed beyond the operating limit of said shear.

4. The improved method of producing billets or bars of relatively small cross-section, by hot rolling in a continuous billet mill, which consists in cutting the stock in said billet mill by a flying shear at an intermediate point in its reduction, and thereafter completing the reduction of the short severed pieces at a speed beyond the operating limit of said shear, whereby to make the capacity of said mill independent of the operating speed limit of said shear.

5. In the art of continuously rolling bars or billets of small cross section, improvement which consists in procuring transverse severance of the stock into short pieces at corresponding weight to the finished commercial bars or billets, while in process of reduction by said continuous rolling.

6. The herein described new method of rolling and shearing metal bars and billets, which consists in roughing the stock in a continuous mill, shearing it to finished weights in a flying shear and then finishing the sheared pieces in one or more additional roll passes.

7. In the production of rolled bars and billets of predetermined equal lengths, the improvement which consists in shearing the stock to the finished weights one or more roll passes in advance of the finishing, thereby permitting full freedom of reduction in the finishing roll passes.

Signed this 15th day of November, 1919.

VICTOR E. EDWARDS.

Certificate of Correction

It is hereby certified that in Letters Patent No. 1,544,565, granted July 7, 1925, upon the application of Victor E. Edwards, of Worcester, Massachusetts, for an improvement in "The Art of Rolling and Shearing Metal Billets or Bars," errors appear in the printed specification requiring correction as follows: Page 2, line 70, claim 5, before the word "improvement" insert the article *the*, and lines 72 and 73, for the words "at corresponding" read *that correspond in*; and that the said Letters Patent should be read with these corrections therein that the same may conform to the record of the case in the Patent Office.

Signed and sealed this 18th day of August, A. D. 1925.
